Assistant Examiner — Samantha K Pollack

(57) **CLAIM**

The ornamental design for a light therapy leg pad as shown and described.

DESCRIPTION

FIG. 1 is a perspective view of a light therapy leg pad showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a perspective view thereof, showing the light therapy leg pad in an open state of use;

FIG. 9 is an enlarged detail view taken from portion 9 of FIG. 1;

FIG. 10 is an enlarged detail view taken from portion 10 of FIG. 5; and,

FIG. 11 is an enlarged detail view taken from portion 11 of FIG. 6.

The broken lines in the drawings indicate enlarged portions which form no part of the claimed design.

1 Claim, 11 Drawing Sheets
